US0D1109354S

(12) **United States Design Patent** (10) **Patent No.:** **US D1,109,354 S**
(45) **Date of Patent:** **** Jan. 13, 2026**

(54) **THERAPEUTIC DEVICE**

(71) Applicant: **Therabody, Inc.**, Los Angeles, CA (US)

(72) Inventors: **Jaime Sanchez Solana**, Los Angeles, CA (US); **Eduardo Merino**, Los Angeles, CA (US); **Alex Zhu**, Xiamen (CN)

(73) Assignee: **Therabody, Inc.**, Los Angeles, CA (US)

(**) Term: **15 Years**

(21) Appl. No.: **29/932,639**

(22) Filed: **Mar. 14, 2024**

Related U.S. Application Data

(63) Continuation of application No. 29/875,794, filed on May 10, 2023, now Pat. No. Des. 1,018,884, which is a continuation of application No. 29/866,590, filed on Sep. 19, 2022, now Pat. No. Des. 988,534.

(57) **CLAIM**

The ornamental design for a therapeutic device as shown and described.

DESCRIPTION

FIG. 1 is a top front isometric view of a therapeutic device showing the claimed design;

FIG. 2 is a bottom rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures show portions of the therapeutic device that form no part of the claimed design.

1 Claim, 6 Drawing Sheets
